UNITED STATES PATENT OFFICE

THOMAS ELLIOTT, OF BIRMINGHAM, ALABAMA, ASSIGNOR TO CONTINENTAL GIN COMPANY, A CORPORATION OF DELAWARE

HULLER GIN

Application filed March 31, 1930. Serial No. 440,490.

My invention relates to huller gins, of the double or single rib type, and is particularly concerned with novel means for effectively cleaning and separating hulls from seed cotton and also for reclaiming any seed that become intermingled with the hulls, whether by dropping into the outer or huller breast in the double rib type of huller gin or by the discharge of the seed with the hulls separated from the cotton in the single rib type of huller gin.

My invention relates to that type of gin in which the entering seed cotton, mixed with hulls and trash, is delivered by any suitable hull board means, preferably one comprising a hull board delivering to a picker roll which in turn delivers the cotton and hulls into engagement with the teeth of the gin saws. In gins of this type the delivery end of the hull board means, which in the construction above described will be a picker roller, defines the opening with reference to the gin saw cylinder through which the hulls must escape and in the case of the double rib huller gins the seed which fall back into the breast from the outer huller ribs must also escape through this opening or passage between the picker roll and the gin saws. The practice has been to reduce this opening or clearance as much as possible without causing the gin to choke up by reason of unduly retarding the escape of the hulls, but the larger the opening the greater the tendency is for the escape of cotton with the hulls, and therefore the practice has been to attempt to regulate the size of this opening empirically with relation to the particular material under treatment so that while allowing a sufficiently free escape of the hulls there would be a minimum loss of cotton therewith.

Various means have been provided for reclaiming the cotton escaping with the hulls in such a construction as has been above described, and my present invention is concerned with the reclaiming of all cotton that passes out with the hulls, and it has the important advantage of permitting the hull escape opening past the gin saws to be enlarged so that no tendency of the hulls to

choke up in the gin breast will occur and yet it will prevent the loss of cotton that passes out with the hulls through this enlarged opening. As a result of this I greatly increase the capacity of the gin which is limited by its tendency to choke.

Furthermore, by the rapid removal of hulls from the gin breast, I avoid the tendency of the saws to cut up the hulls and carry the resulting hull particles and shale onto the ginning roll box and thereby I prevent a lowering of the grade of the cotton ginned.

Another important feature of my invention lies in the fact that it is equally applicable for use with clean cotton as with very hilly cotton or bolly cotton, and in either case it will effectively reclaim all cotton passing out with the hulls and trash through the hull escape opening from the gin breast.

More particularly, my invention contemplates interposing below the hull board means a reclaiming saw cylinder of reduced diameter as compared with the gin saw cylinder but preferably having a like direction of rotation and I associate with these reclaiming saws a guide board, preferably concavo convex in shape and also preferably provided with perforations suitable for the escape of seed. This guide board extends under the reclaiming saws and rises to a sufficient height on the side of said reclaiming saws remote from the gin saws so as to cause a slight back pressure of hulls as they overflow its discharge edge, this back pressure holding the hulls and trash in position to be stripped of cotton by the reclaiming saws. Moreover, this back pressure can be regulated by an adjustment of the height of the overflow edge so as to press the overflowing mass of hulls against the reclaiming saws in such manner as to complete the reclaiming of cotton from the hulls before permitting their overflow and escape.

Where the huller gin is of the single rib type all of the seed and hulls pass over the guide board leading to the reclaiming saws and the seed will fall through the perforations in said board and thus separate themselves effectively from the hulls.

- A further important feature of my invention lies in the fact that the reclaiming saws can be driven at a very low peripheral speed, thus acting to prevent a tendency which would result from high peripheral speed of the teeth on its up-going side to throw hulls over the overflow edge of its guide board before they have been cleaned of cotton.
- 10 A further advantage of my invention in its preferred form, lies in the fact that the reclaiming saws, rotating in the same direction as the gin saws, will act as a positive means to engage and move the hulls escaping from the gin breast away from position under the opening between the hull board means and the gin saws, thereby insuring against the hulls accumulating in the gin breast with the disadvantages above pointed out.
- 15 A further important advantage of my invention lies in the fact that it is capable of ready application as an attachment to existing huller gins.
- 20 25 My invention further comprises the novel details of construction and arrangements of parts, which in their preferred embodiment are illustrated in the accompanying drawings, which form a part of this specification and which show in vertical transverse cross-section a view of a conventional type of double rib huller gin with my improved cotton reclaiming attachment.
- 25 30 As embodied in the drawings, I show a conventional huller gin comprising the gin breast 1 having an inclined hull board 2 which delivers the seed cotton, hulls, trash, etc., entering the gin breast to a picker roll 3, forming part of the hull board means which acts to deliver the material to be treated into engagement with the teeth of the gin saws 4, which work between outer hulling ribs 5 and inner ginning ribs 6 in the usual manner. Hulls, stripped from the seed cotton by the ribs 5 are carried by the clockwise rotation of the picker roller 3 downwardly past the saws 4 and are delivered to the reclaiming mechanism. The hull board 2 terminates in spaced relation with the tips of the spikes on the picker roller 3, leaving sufficient clearance for cotton to pass back up from the reclaiming mechanism into the gin breast to be treated again by the gin saws, but not leaving sufficient opening to permit any appreciable amount of cotton, hulls or the like to pass directly to the reclaiming mechanism. The passage through which the hulls escape from the gin breast between the picker roller 3 and the gin saws 4 is indicated by the numeral 8 and this passage or opening is large enough to permit a free escape of hulls from the gin breast, this escape being aided by the positive action of the picker roller spikes 65 on the hulls. The hulls and any cotton to

be reclaimed therefrom escaping through the opening 8 pass onto a concavo-convex guide plate 9 which has a free outer edge forming an overflow lip 10 over which the hulls escape after being cleaned by the action of the reclaiming saws 11.

The reclaiming saws 11 are materially smaller in diameter than the gin saws 4 and are preferably driven by any suitable means, not shown, in the same direction on the gin saws. They will therefore tend to engage the hulls as they pass onto the guide board 9 and will drive them around under the saws 11 and towards the overflow lip 10. Here the hulls will accumulate between the guide board and the reclaiming saws and as they accumulate they will create a back pressure or resistance to the action of the reclaiming saws as the latter pass through the mass of hulls. This accumulation of the hulls before they overflow serves to hold them in proper relation to the traveling reclaiming saws 11 to enable the latter to work through the hulls and to pick up and remove therefrom the cotton that would otherwise escape. This cotton is doffed from the reclaiming saws by the doffing brush 13 which will deliver it to the picker roller 3 which will carry it upwardly into the gin breast and return it to the gin saws 4.

25 30 A suitable guard 14 is provided for the doffing brush 13 and any suitable adjustment means may be provided for the guide board 9, such as the eccentric 12, which will act to vary the clearance between the guide board 9 and the saws 11 and also to vary the height of the overflow lip 10, thus regulating the resistance of the overflowing mass of hulls to the reclaiming saws. To separate seed from the hulls, I preferably provide suitable perforations or apertures, as at 15, in the guide board 9 adapted to permit any seed that fall outwardly from the huller ribs 5 and enter the opening 8 to be separated from the hulls and recovered. In the case of single rib huller gins all of the seed will pass over the guide board 9 and in such case a greater portion of its surface should probably be provided with apertures 15 for the escape of the seed.

35 40 The guard 14 is extended close enough to the saw cylinder 11 to knock back hulls tending to pass over with this saw cylinder to the doffing brush 13. It thus serves as a suitable stripping means for the reclaiming saws.

45 50 It is important to note that the reclaiming saws can be driven at a very slow peripheral speed as contrasted with that of the gin saws. For instance, I have obtained very satisfactory results where the peripheral speed of the reclaiming saws was about 7% of that of the gin saws. The advantage of this slow speed is that the teeth of saw 11 do not travel fast enough up through the mass of hulls to tend to throw them out by centrifugal force which

might cause the ejection of hulls before they are cleaned of any adhering locks of cotton. When the reclaiming saw teeth move upwardly slowly through the mass of hulls adjacent to the overflow lip 10, they gradually force the overflow of hulls, but the hulls remain in position long enough to insure that the teeth will reclaim the cotton therefrom before they are discharged.

10 In the operation of my invention for the treatment of seed cotton which is practically free from hulls, due to the large clearance provided between the picker roller 3 and the gin saws 4, a substantial amount of cotton 15 will tend to escape through the passage 8 but it will all be caught by the reclaiming saws 11 and returned by its doffing brush to the picker roller 3 and by that roller again returned to the gin saws and recovered, so that 20 it will not be lost.

Where a large amount of hulls and trash are present in the seed cotton, these hulls will be knocked back by the huller ribs from the gin saws and will be carried out by the action 25 of the picker roller and will pass through the opening 8 onto the guide board 9 and thence into engagement with the teeth of the reclaiming saws 11 which, moving in the same direction as to that of the falling hulls, will 30 drive them under the reclaiming saws toward the space between the saws 11 and the overflow edge 10 of the guide board. The hulls will accumulate in this last mentioned space with the saws 11 working up through them 35 until they begin to overflow the edge 10 and after this the action will be continuous, hulls overflowing the lip 10, and seed escaping through the apertures 15 and such cotton as may pass from the ginning breast with the 40 hulls will be reclaimed by the teeth of the saws 11 doffed by the brush 13, and returned by the picker roller 3 to the gin saws 4.

The purpose of the adjustment 12 will be obvious for where there are but few hulls the 45 guide board 9 should be spaced so that the saws 11 will be sure to contact with such hulls and thus will have a better opportunity to strip of any cotton adhering thereto, but where there is a large amount of hulls and trash the 50 guide board can be lowered to increase the clearance and avoid any tendency of the reclaiming saws to be choked or to unduly cut up the hulls.

Where I refer to reclaiming saws, I may use 55 the customary saw cylinder or any equivalent means which will serve to engage the cotton and strip it from the hulls.

While my present invention is applicable to other uses than as the reclaiming agency in a 60 huller gin, my present invention is confined to this particular application.

What I claim is:—

1. In a huller rib gin, the combination with the gin breast having gin saws and a hull 65 board means for delivering the seed cotton

to said saws, of reclaiming saws disposed below said hull board means and rotatable in the same direction as the gin saws, means to guide the hulls and cotton escaping between said gin saws and hull board means 70 into engagement with said reclaiming saws, means to accumulate hulls on the upgoing side of said reclaiming saws in position to be engaged and stripped of cotton by said reclaiming saws before being discharged, and 75 means to doff cotton from said reclaiming saws and return it to the gin saws.

2. The combination with a huller rib gin having in its breast gin saws, a hull board, and a picker roller working between said hull board and saws, of reclaiming saws and doffing means therefor mounted below said hull board, and means to cause hulls escaping between the said roller and gin saws to accumulate in position to be stripped of cotton 80 by the upgoing side of said reclaiming saws, said roller being disposed to receive the cotton doffed from the reclaiming saws and return same to the gin breast.

3. The combination with a huller rib gin 85 having in its breast gin saws, a hull board, and a picker roller working between and in spaced relation to said hull board and saws, of reclaiming saws and doffing means therefor mounted below said hull board, and means to cause hulls escaping between the said roller and gin saws to accumulate on the upgoing side of said reclaiming saws in position to be stripped of cotton by said reclaiming saws, said roller being disposed to receive 90 the cotton doffed from the reclaiming saws and return same to the gin breast.

4. In a huller rib gin, the combination with a gin breast having gin saws and a hull 100 board means comprising an inclined hull board and a picker roller coacting with the gin saws, of reclaiming saws disposed below said hull board means, means to guide hulls and cotton falling between said roller and the gin saws into engagement with said reclaiming saws, means to cause hulls to accumulate on the upgoing side of said reclaiming saws in position to be engaged and stripped of cotton by said latter saws before being discharged, and means to doff cotton from said 105 reclaiming saws and deliver it to said picker roller.

5. In a huller rib gin, the combination with a gin breast having gin saws and a hull board 110 means comprising an inclined hull board and a picker roller coacting with the gin saws, of reclaiming saws disposed below said hull board means, means to guide hulls and cotton falling between said roller and the gin saws into engagement with one side of said reclaiming saws, means to cause hulls to accumulate on the other side of said reclaiming saws in position to be engaged and stripped of cotton by said latter saws before being discharged, and means to doff cotton from said 115 120 125 130

reclaiming saws and deliver it to said picker roller, said picker roller and reclaiming saws having the same direction of rotation as the gin saws.

5 6. In a huller rib gin, the combination with a gin breast having gin saws and a hull board means comprising an inclined hull board and a picker roller coacting with the gin saws, of reclaiming saws disposed below said hull board means, means to guide hulls and cotton falling between said roller and the gin saws into engagement with said reclaiming saws, means to cause hulls to accumulate on the upgoing side of said reclaiming saws in position to be engaged and stripped of cotton by said latter saws before being discharged, and means to doff cotton from said reclaiming saws and deliver it to said picker roller, the picker roller being disposed between the reclaiming saws and the gin saws.

10 7. In a huller rib gin, the combination with a gin breast having gin saws and a hull board means comprising an inclined hull board and a picker roller coacting with the gin saws, of reclaiming saws disposed below said hull board means, means to guide hulls and cotton falling between said roller and the gin saws into engagement with said reclaiming saws, means to cause hulls to accumulate in position to be engaged and stripped of cotton while being kicked upwardly and discharged by said reclaiming saws, and means to doff cotton from said reclaiming saws and deliver it to said picker roller, said picker roller being discharged between the gin saws on one side and the hull board, the reclaiming saws and their doffing means on the other side.

15 8. The combination with the breast and saws of a huller rib gin, of reclaiming saws, hull guide means adapted to deliver hulls escaping from said gin breast under and beyond said reclaiming saws and having its hull discharge edge raised to cause hulls to accumulate in the space between it and said reclaiming saws before being discharged, means to doff the reclaiming saws, and means to return the doffed cotton to the gin saws.

20 9. The combination with the breast of a huller rib gin, of reclaiming saws, hull guide means adapted to deliver hulls escaping from said gin breast under and beyond said reclaiming saws and having its hull discharge edge raised to cause hulls to accumulate in the space between it and said reclaiming saws before being discharged, means to doff the reclaiming saws, and means to return the doffed cotton into the gin breast, the reclaiming saws being rotatable so that their teeth rise through the accumulated hulls.

25 10. The combination with the breast of a huller rib gin, of reclaiming saws, hull guide means adapted to deliver hulls escaping from said gin breast under and beyond said reclaiming saws and having its hull discharge edge raised to cause hulls to accumulate in

the space between it and said reclaiming saws before being discharged, means to doff the reclaiming saws, and means to return the doffed cotton into the gin breast, the reclaiming saws being rotatable so that their teeth rise through the accumulated hulls at a speed sufficiently low to avoid peripherally ejecting hulls from said space into the discharge.

15 11. The combination with a huller rib gin having a gin breast, gin saws and hull board means spaced from said saws to provide for a free escape of hulls from said breast, of a cotton reclaiming means adapted to treat the escaping hulls and comprising means to collect said hulls in a space from which they gradually and freely overflow, reclaiming saws disposed to work through the hulls collected in said space and strip them of cotton before they overflow, and means to doff the reclaiming saws and return the doffed cotton to the gin breast.

20 12. The combination with a huller rib gin having a gin breast, gin saws and hull board means spaced from said saws to provide for a free escape of hulls from said breast, of a cotton reclaiming means adapted to treat the escaping hulls and comprising means to collect said hulls in a space from which they gradually and freely overflow, reclaiming saws disposed to work through the hulls collected in said space and strip them of cotton before they overflow, and means to doff the reclaiming saws and return the doffed cotton to the gin breast, the saws being rotated so as to engage and feed the hulls as they escape from the gin breast into the bottom of said space.

25 13. In a huller rib gin according to claim 1, the combination with the reclaiming saws, of a stripping means disposed in advance of the means to doff said saws.

In testimony whereof I affix my signature.
THOMAS ELLIOTT.
